UNITED STATES PATENT OFFICE.

MICHAEL H. COLLINS, OF WEST HOBOKEN, NEW JERSEY.

RAILWAY SIGNALING SYSTEM.

1,090,825.

Specification of Letters Patent. Patented Mar. 17, 1914.

Application filed March 5, 1913. Serial No. 752,059.

To all whom it may concern:

Be it known that I, MICHAEL H. COLLINS, a citizen of the United States, and a resident of West Hoboken, in the county of 5 Hudson and State of New Jersey, have invented a new and Improved Railway Signaling System, of which the following is a full, clear, and exact description.

The invention relates to automatic and interlocking block signals for electric and steam railways having continuous track rails, and its object is to provide a new and improved railway signaling system arranged to provide an efficient shunting protection 15 with a view to prevent collisions and to set the signal to danger in case of a broken rail in a block, and to dispense with insulated joints, reactance bonds, impedance coils and the like.

For the purpose mentioned use is made of 20 transformers at the entrance and exit ends of a block, each transformer having a primary and a secondary coil, of which the primary coil is connected with the track rails 25 and its resistance corresponds approximately to that of the portions of the track rails between the entrance transformer of one block and the exit transformer of the adjacent block, the secondary coil of a transformer being connected with a polyphase 30 relay controlling a corresponding block.

A practical embodiment of the invention is represented in the accompanying drawings forming a part of this specification, in 35 which similar characters of reference indicate corresponding parts in all the views.

Figure 1 is a diagrammatic view of the railway signaling system provided with three-phase relays; Fig. 2 is an enlarged 40 plan view partly in section of one of the track transformers; Fig. 3 is a sectional side elevation of the same, on the line 3—3 of Fig. 2; Fig. 4 is a diagrammatic view of a portion of the railway signaling system 45 provided with two-phase relays; Fig. 5 is a side elevation of the three-phase relay; Fig. 6 is a sectional side elevation of the same; and Fig. 7 is a sectional plan view of the same on the line 7—7 of Fig. 5.

In the general construction of the railway 50 signaling system, as shown in Fig. 1, use is made of conductively, continuous, bondless track rails A, A', an alternating current power line B, B' connected with an alter-

nating generator or transformer (not shown), and signals C, C', C² of the usual semaphore type and located at the entrance of blocks I, II, III. The power line B, B' is connected by transformers D and track circuit wires E, E', with the rails A, A' 60 approximately at the middle of each block to energize the track rails.

Near the entrance and exit ends of each block I, II, III, etc., are arranged relay controlling transformers F, F' each having a primary coil F² connected at its ends with the track rails A and A' and having a resistance which corresponds approximately to that of the portion of a track rail extending between the entrance relay controlling 70 transformer F of one block and the exit relay controlling transformer of the preceding block. In practice the relay controlling transformers F and F' of adjacent blocks are placed from ten to twenty-five feet apart, 75 so that a modern car G straddles the distance, and the resistance of each primary coil is made to correspond approximately to that of the ten to twenty-five feet of track rail mentioned. The car G is represented as traveling in the direction of the arrow a' on the track rails A, A'. The secondary coil F³ of the transformer F is connected with a polyphase relay H, and the secondary coil F'³ of the transformer F' is 80 connected with a similar polyphase relay H' electrically connected with the transformers D, D' of the power line B, B'.

As shown in Fig. 1 the relays H, H' are of the three-phase type, while the relay 90 shown in Fig. 4 is of the two-phase type; otherwise, the arrangement is the same as above described relative to the parts mentioned. The relays H, H' control the signal circuits I, I' to allow the semaphores to 95 move from normal safety position to danger position, as hereinafter more fully explained.

Of the three phases 1, 2 and 3, of each relay H, H', the phase 1 is connected with the secondary F³ of the corresponding transformer F or F', the phase 2 is connected with the source of electrical energy at the 100 transformers D, and the phase 3 is controlled through a front contact 4, which in turn is operated from the rotor of the relay H or H'. The rotor of the relay is in turn operated from the primary of the track transformer F or F' and by energy by way of the 105

phase 2. The contact 5 is connected with the signal circuits I, I' and is controlled by the rotor of the relay as hereinafter more fully described.

- 5 The rotor of the three-phase relay H or H' is divided into two mechanical parts, 6 and 7 (see Fig. 7) having shafts 8 and 9 hung on centers in a suitably constructed frame 10. These rotor parts 6 and 7 are designed to 10 revolve in opposite directions. On the shafts 8 and 9 are mounted pinions 11 and 12 in mesh with weighted segmental gear wheels 13 and 14 attached to shafts 15 and 16 journaled on the frame 10. On the shafts 15 15 and 16 are secured crank arms 17 and 18 pivotally connected with contact bars 19 and 20 of the contacts 4 and 5 respectively. The contact bars 19 and 20 are provided with pins 21 and 22 slidably engaging bearings 23 and 24 held on the frame 10. The contact 5 is connected with the signal circuit wire I and is adapted to make contact with the contact 25 fixed on the frame 10 and connected with the other signal circuit wire I'. 25 The contact 4 is connected by a wire 26 with the phase 2 and is adapted to make contact with a contact 27 fixed on the frame 10 and connected by a wire 28 with phase 3. The phase 1 is opposite rotor part 6; the 30 phase 3 is opposite rotor part 7; and the phase 2 is opposite both rotor parts 6 and 7, as plainly indicated in Fig. 7. The up and down swinging motion of the segmental gear wheels 13 and 14 is limited by stop pins 29 and 30 on the frame 10.

Contacts 4 and 5 of the relays H and H' are normally in closed position, that is, when no car or train is in the block and the segmental gear wheels 13 and 14 are then in 40 raised position as shown in Fig. 6.

It is understood that when a block is free of a train the electric current from the transformer D passes by way of the wires E, E' to the track rails A, A' and to the primaries 45 F² of the relay controlling transformers F and F' of the block, so that the secondaries F³ of the said relay controlling transformers F and F' are energized and the induced current passes to phase 1 of the rotor part 6 50 whereby the latter is rotated and the rotary motion is transmitted by the pinion 11 to the segmental gear wheel 13 to swing the latter upward and thereby rotate the shaft 15. The rotary motion of the shaft 15 causes the 55 contact bar 19 to move to the left whereby the contact 4 moves into contact with the contact 27 thus closing the circuit for the phase 3 whereby the rotor part 7 is rotated. The rotary motion of the rotor part 7 is 60 transmitted by the pinion 12 to the segmental gear wheel 14 whereby the latter is swung upward and in doing so turns the shaft 16 so that the contact bar 20 is moved to the right and the contact 5 moves into 65 closed position relative to the contact 25,

thus closing the signal circuit I, I' to cause the signal to go to safety position.

When a car moves into the block the track rails are short-circuited by way of the car and hence the relay controlling transformer F of this block is cut out so that the phase 1 is deenergized to relieve the rotor part 6. When this takes place the weighted segmental gear wheel 13 swings downward by its own gravity whereby the contact bar 19 70 is shifted to the right and the contact 4 moves into open position thus breaking the circuit for the phase 3 to release the rotor part 7. When this takes place the weighted segmental gear wheel 14 swings downward by its own weight and in doing so shifts the contact bar 20 to the left to move the contact 5 into open position relative to contact 25 thus breaking the signal circuit I, I' and allowing the signal at the entrance of the 80 block to go to danger position.

The reason for using the third phase 3 is to obtain a strong torque on the rotor to insure a good, strong contact, but a two-phase relay may be used, as shown in Fig. 4. 90

The track wires E, E' of adjacent blocks are reversely connected with the track rails A, A' to reverse the polarity of the primary coils F² of adjacent transformers F and F'. It is understood that if the polarity of the 95 primary coils F² of the transformers F and F' were the same, sufficient current might pass from the transformer F' to the transformer F to keep the relay H energized and closed until the following car was close to 100 the transformer F'.

As previously mentioned, the signals C, C', C² are normally in safety position and the controlling signal circuits I, I' are closed at the relays H, H'. Now when a car G 105 moves into the block II and passes the transformer F then the signal C' moves into danger or stop position and the signal C' remains in this position as long as the car is in block II.

It is understood that when the front wheels of a car G pass the transformer F at the entrance end to the block II, they short-circuit the track rail current, and consequently the primary F² and the secondary 115 F³ of the transformer F are deenergized and the relay H is opened to influence the signal circuits I, I' for the signal C', and thereby allow the said signal C' to swing downward into danger or stop position.

When the car G has passed the track wires E, E' of block II the relay H of this block closes, that is, both contacts 4 and 5 move successively into contact with the contacts 27 and 25, as previously explained, but as the 125 contact 5 of relay H' of block II is open the original circuit I, I' remains open until the car has passed the actuating relay transformer F' at the end of the block II. When this takes place the relay H' of block II is 130

energized and the contacts 4 and 5 of this relay move successively into closed position whereby the signal circuit I, I' for the signal C' is closed to cause the signal C' to move 5 into safety position.

- It will be noticed that by the arrangement described the relay H of a block is actuated as soon as the car enters the block and as said relay controls the signal circuits I, I' 10 for this particular block the signal moves to danger position and positively remains therein until the car G leaves the block. As previously stated, the distance between the transformers F and F' in blocks II and III 15 is straddled by a car, and it follows that the signal C' only moves back to safety position after the signal C² has moved into danger or stop position.

From the foregoing it will be seen that 20 by the use of the transformers F and F' arranged as described the exact limits of the block are determined and proper protection is afforded to an approaching car or train.

- 25 It will be noticed that the track current supplied by the wires E, E' for any one block is prevented from flowing into any other block, because the primaries of the transformers F and F' act as cross-bonds 30 to short-circuit the track current to prevent the same from entering another block.

It is understood that the resistance of the primary coil F² of each transformer F and F' is determined as previously explained according to the total resistance of the length of the track desired between the transformers of adjacent blocks, so that the track relay is picked up after the car or train has passed the limits of the block. By making 40 the resistance of the primary coil equal to or less than that of a given length of track and locating the transformers F, F' of opposite polarity and of adjacent blocks the predetermined distance apart the track rail 45 current supplied to the rails in one block is prevented from flowing into the next block and hence there is no danger that the relay in the next block is affected.

It is understood that the transformers F 50 and F' are used on conductively continuous and cross-bondless track rails and actuate the relays H and H', and each transformer has the function of an ordinary transformer and that of a cross-bond for the track rails.

55 Having thus described my invention, I claim as new and desire to secure by Letters Patent:

1. In a railway block signal system, conductively continuous cross-bondless track 60 rails of substantially uniform impedance, a source of electrical energy connected with the rails at each block, a pair of relay controlling transformers for each block, one of the transformers of each pair being located at the entrance end of a block and the

other at the exit end thereof, each transformer having a primary coil and a secondary coil, the primary coil being connected with the said rails and having a resistance corresponding approximately to the resistance of the track rail portion between the adjacent transformers of adjacent blocks, and relays controlling the signal and connected with the said secondary coil of the said relay controlling transformers. 70

2. In a railway block signal system, conductively continuous cross-bondless track rails of substantially uniform impedance, a source of electrical energy connected with the rails at each block and with the polarity reversed for succeeding blocks, a pair of relay controlling transformers for each block, one of the transformers of each pair being located at the beginning end of the block and the other at the exit end thereof, 80 each transformer having a primary coil and a secondary coil, the primary coil being connected with the said rails and having a resistance corresponding approximately to the resistance of the track rail portion between the adjacent transformers of adjacent blocks, and relays controlling the signal at the entrance of a block and connected with the said secondary coil of the relay controlling transformers of the same block. 85

90 3. In a railway block signal system, conductively continuous cross-bondless track rails of substantially uniform impedance, signal-controlling circuits, a source of electrical energy connected with the rails of a block, relays at opposite sides of the said source for jointly controlling one of said circuits, relay controlling transformers arranged at the ends of each block and each having a primary coil and a secondary coil, 100 the primary coil being connected with the track rails, and having a resistance corresponding approximately to that of the length of the track rails between the adjacent transformers of adjacent blocks, and the secondary coil being connected with the corresponding relay. 105

110 4. In a railway block signal system, conductively continuous cross-bondless track rails of substantially uniform impedance, signal-controlling circuits, a source of electrical energy connected with the rails of a block, relays at opposite sides of the said source for jointly controlling one of said circuits, relay controlling transformers arranged at the ends of each block and each having a primary coil and a secondary coil, the primary coil being connected with the track rails and having a resistance corresponding approximately to that of the length of the track rails between the adjacent transformers of adjacent blocks, and the secondary coil being connected with the corresponding relay, one of said relays having two parts, one of said parts being con- 115 120 125 130

trolled by the other part to open and close said circuit in response to said other part, and a signal operated by said signal circuit.

5. In a railway block signal system, conductively continuous cross-bondless track rails of substantially uniform impedance, a source of electrical energy connected with the track rails at each block, a signal at the beginning end of each block, two relays for each signal, and relay controlling transformers at the entrance and exit ends of each block, each transformer having a primary coil and a secondary coil, of which the primary coil is connected with the track rails and has a resistance corresponding approximately to that of the portion of the track rails between the entrance transformer of one block and the exit transformer of the adjacent block in the rear, the said secondary coil of a transformer for a signal being connected with one of the relays for this signal.

6. In a railway block signal system, conductively continuous cross-bondless track rails of substantially uniform impedance, signals at the entrance ends of the blocks, an electrical source of energy connected with the rails of each block, relay controlling transformers for each block, one at the entrance end of a block and one at the exit end thereof, each transformer having a primary coil and a secondary coil, of which the primary coil is connected with the track rails and has a resistance corresponding approximately to that of the rail portion between the entrance transformer of one block and the exit transformer of the adjacent block in the rear, and relays each having three windings, one relay for each relay controlling transformer and controlling the said signals, each relay having one winding connected with the secondary coil of the corresponding relay controlling transformer.

7. In a railway block signal system, conductively continuous cross-bondless track rails of substantially uniform impedance, signals at the entrance ends of the blocks, an electrical source of energy connected with the rails of each block, relay controlling transformers for each block, one at the entrance end of a block and one at the exit end thereof, each transformer having a primary coil and a secondary coil, of which the

primary coil is connected with the track rails and has a resistance corresponding approximately to that of the rail portion between the entrance transformer of one block and the exit transformer of the adjacent block in the rear, and relays each having three windings, one relay for each relay controlling transformer and controlling the said signals, each relay having one winding connected with the secondary coil of the corresponding relay controlling transformer, each relay having another winding connected with the source of electrical energy, and each relay having the third winding controlled by the joint action of the first and second windings.

8. In a railway block signal system, conductively continuous cross-bondless track rails of substantially uniform impedance, signals at the entrance ends of the blocks, an electrical source of energy connected with the rails of each block, relay controlling transformers, one at the entrance end of a block and one at the exit end thereof, each transformer having a primary coil and a secondary coil, of which the primary coil is connected with the track rails and has resistance corresponding approximately to that of the rail portion between the entrance transformer of one block and the exit transformer of the adjacent block in the rear, and relays each having three windings, one relay for each relay controlling transformer and controlling the said signals, each relay having a rotor and having one winding connected with the primary coil of the corresponding relay controlling transformer, the second winding of each relay being connected with the source of electrical energy and the third winding of each relay being controlled by the said rotor, the latter being controlled by the first winding connected with the primary coil of the relay controlling transformer and by the energy supplied to the second winding.

In testimony whereof I have signed my name to this specification in the presence of two subscribing witnesses.

MICHAEL H. COLLINS.
